United States Patent Office

Des. 224,891
Patented Oct. 3, 1972

224,891

HEATER BACK PAN

Jay N. Smith, Wichita, Kans., assignor to Impala
Industries, Inc., Wichita, Kans.

Filed Sept. 28, 1970, Ser. No. 25,226

Term of patent 14 years

Int. Cl. D23—03

U.S. Cl. D23—127

FIG. 1

FIG. 2

FIG. 3

FIG. 1 is a perspective view of a heater back pan showing my design;

FIG. 2 is a side elevational view thereof;

FIG. 3 is a top plan view thereof, the bottom being identical.

The rear of the back pan is flat and unornamented.

I claim:

The ornamental design for a heater back pan, as shown and described.
